J. SCHARL,
METHOD OF MAKING SPARK PLUG INSULATORS,
APPLICATION FILED DEC. 18, 1918.

1,343,686.

Patented June 15, 1920.

UNITED STATES PATENT OFFICE.

JOHN SCHARL, OF NEW YORK, N. Y., ASSIGNOR TO GENERAL CERAMICS COMPANY, OF JERSEY CITY, NEW JERSEY, A CORPORATION OF NEW JERSEY.

METHOD OF MAKING SPARK-PLUG INSULATORS.

1,343,686.

Specification of Letters Patent. Patented June 15, 1920.

Application filed December 18, 1918. Serial No. 267,240.

To all whom it may concern:

Be it known that I, JOHN SCHARL, a citizen of Hungary, and a resident of New York city, in the county and State of New York, have invented a new and useful 5 Method of Making Spark-Plug Insulators, of which the following is a specification.

This invention relates to a method of 10 making an insulator which is designed to form a component part of a spark plug and which possesses numerous advantages over the porcelain insulators now generally used, particularly for the reason that it is not liable to crack under sudden changes of 15 temperature. Such changes are frequently encountered by flying machines.

In the accompanying drawing:

Figure 1 is a diagrammatic sectional elevation of an apparatus for carrying my invention into effect;

Fig. 2, a vertical cross section showing the mold open;

Fig. 3, a similar section showing the mold closed;

Fig. 4, a horizontal section showing the electrodes;

Fig. 5, a diagrammatic cross section of a modification, and,

Fig. 6, a perspective view of an insulator 30 complete.

The body of the insulator 5 (Fig. 6) has the conventional or any other shape desired, and is provided with a longitudinal bore for the reception of one of the terminals.

I propose to form the insulator of the material known as fused silica or silica glass, which is generally obtained by subjecting a quantity of quartz sand to a high 40 temperature in an electric furnace so as to fuse the sand into a homogeneous body.

In order to form the insulator from this material, I use an electrically heated mold formed of an upper section 6, and a lower 45 section 7. The mold may be operated in

suitable manner (not shown) and is provided with rods 8 engaging tubular guides 9. The contour of the mold is such as to form the body 5 together with the usual 50 collar 10, while the edges of the mold are beveled as at 11, to discharge the overflow.

Centered between the mold sections is a pair of divided parallel spindles 12, which are spaced from each other and are pro-

vided with holders 13. The spindles are 55 intergeared at 14, and may be simultaneously rotated by a crank handle 15, a small motor, or in other manner. Upon a rock shaft 16 (operated in suitable manner, not shown) is mounted a pair of bent arms 17 having hook shaped ends 18 that are adapted to grasp a wooden or other core 19, the correlation of the parts being such that when the arms are swung up, they will center the core between spindles 12, and in parallelism therewith.

The apparatus described forms part of or directly adjoins an electric furnace, the drawing showing an arc furnace having three electrodes 20 that face and heat the 70 material mounted upon the spindles 12.

In use, a pair of fused quartz tubes, rods, plates, or similar bodies 21 are fitted into the holders 13 of spindles 12, so that such tubes assume a spaced parallel relation. 75 Upon the ends of tubes 21, is slipped a pair of baffle plates 22 that confine the heat to the central portions thereof. The spindles are turned to rotate the tubes and the current is turned on, to reheat the tubes, until 80 they become soft or plastic, whereupon the spindles are arrested and the current is shut off. A core 19 fitted into arms 17, is carried between the softened tubes, by the turning shaft 16. This core consists preferably 85 of a stick of wood or other combustible material which may be treated with asbestos or other liquid which retards the combustion. The molds 6, 7 are closed to unite the tubes 21 into a single body, and to impart to such body the desired contour of the insulation 5. During this shaping, the core 19 will be eventually consumed and in this way the insulation is made tubular or provided with the axial bore required for the 95 reception of one of the spark plug terminals. Should the core for some reason not be entirely consumed, it may be drilled out with little expense.

After the mold is opened, the finished insulation is removed, and after being cooled is ready to be incorporated into the spark plug.

With the embodiment illustrated in Fig. 5, the mold sections 23 are out of vertical 105 alignment with the spindles carrying the fused quartz rods 24, and are separated therefrom by a movable baffle plate 25. Op-

posite the rods 24, are the electrodes 26, while the core 27 is adapted to be centered between the mold sections. With this construction, the quartz rods 24 are heated, the 5 baffle plate 25 is withdrawn, the spindles are shifted to a position between the mold sections, the core is introduced between the quartz rods, and the mold sections are closed as previously described, to produce the 10 tubular insulation desired.

In lieu of using a combustible core, a rod 15 of platinum, tungsten, or other metal having a high melting point may be used. Such a rod should be drawn out quickly after the 20 molding operation has been finished and before the tube has set.

If desired, the silica glass initially operated upon by my process, may contain a small percentage of a flux, so as to increase 25 its fusibility.

I claim:

1. In the method of making a spark plug insulator, that step which consists in re-fusing 20 a silica glass body to render the same

plastic and then folding such plastic body 25 upon a core.

2. In the method of making a spark plug insulator, that step which consists in re-fusing 25 a silica glass body to render the same plastic and then folding such plastic body 30 upon a combustible core.

3. The method of making a spark plug insulator which consists in rotating a pair of silica glass bodies, heating the same and then uniting them into a single body by 35 molding them.

4. The method of making a spark plug insulator which consists in rotating a pair of silica glass bodies, heating the same, introducing a core between the bodies and 40 then molding them upon the core.

5. The method of making a spark plug insulator which consists in rotating a pair of silica glass bodies, heating the same, introducing a combustible core between the 45 bodies and then molding the bodies upon the core.

JOHN SCHARL.
